UNITED STATES PATENT OFFICE.

JAMES KECK, OF DWIGHT, ILLINOIS.

IMPROVEMENT IN CAR-COUPINGS.

Specification forming part of Letters Patent No. **145,428**, dated December 9, 1873; application filed April 24, 1873.

To all whom it may concern:

Be it known that I, JAMES KECK, of Dwight, in the county of Livingston and State of Illinois, have invented a new and useful Improvement in Car-Couplings; and I do declare that the following is a true and accurate description thereof, reference being had to the accompanying drawings and to the letters of reference marked thereon, and being a part of this specification, in which—

Figure 1 is a perspective view of a car fitted with my improvement. Fig. 2 is a detached perspective view of my improved coupling-iron. Fig. 3 is a longitudinal vertical section of a pair of my improved couplings attached to two cars coupled by them.

Like letters refer to like parts in the several figures.

The nature of this invention relates to an improvement in car-couplings of that class which are known as "harpoon couplings," and which automatically couple two cars fitted with them when the said cars come together, and so arranged as to be disconnected from the top of the car, one of the objects of the invention being to enable train-men to uncouple box freight-cars from the top. The invention consists in the peculiar construction of the draw-bars with a harpoon-head, for coupling any two of them together, and the arrangement of their supporting-springs.

In the drawing, A represents the floor of a box-car, and B B the longitudinal bumper-sills under its end. C is my improved draw-bar, pivoted between the sills B by a pin, a, passing through a horizontal longitudinal slot, b, near its inner end, which allows the draw-bar to have the necessary longitudinal play. The outer part is supported by a strong spiral or other spring, D, in a frame, e, pendent from the sills B, which spring presses the draw-bar upward against the bottom of the car. The outer end of the draw-head is enlarged, and in front of that it is retracted in thickness, so as to have a wide but thin neck, e, beyond which the draw-bar is enlarged again, and then ta-

pered to a point, giving the end a form of the harpoon, so that when two cars fitted with such couplings come together one harpoon will override the other until their respective barbs interlock. In this position they are held by their respective springs.

To prevent the harpoons from uncoupling by the lateral swaying of the cars, the point of each harpoon has a vertical slot, f, formed in it which embraces a rib, g, formed on the shoulder of the opposing coupling, which will prevent the uncoupling, unless one car should jump the track, in which case it will not drag the succeeding car after it. At the base of the slot a longitudinal link-socket, h, is formed in the harpoon-head, with which a vertical pin-hole, i, intersects, so that the car may be coupled with another provided with the ordinary link-and-pin coupling.

To uncouple the cars, a bracket, F, is erected at the top of the car-end, to which one end of a lever, G, is pivoted, to which is pivoted the upper end of a rod, H, the lower end of which is secured to an eye in the top of the draw-head. By depressing the lever of the coupling which happens to be lowermost, the latter is forced down out of engagement with the other.

To prevent a car from coupling again, the lever plays between a pair of vertical standards, I, on the roof of the car, having a number of holes drilled through them, through any pair of which a pin may be passed above the lever, and thus keep the coupling-hook from rising to the coupling-plane.

What I claim as my invention, and desire to secure by Letters Patent, is—

The draw-bar C, having a harpoon-head, with the vertical slot f, pin-hole i, and rib g, in combination with the spring D, adapted to operate with a draw-head of similar construction, as set forth.

JAMES KECK.
